UNITED STATES PATENT OFFICE

HARRY E. NORVIEL, OF ANDERSON, INDIANA, ASSIGNOR TO DELCO-REMY CORPORATION, OF DAYTON, OHIO, A CORPORATION OF DELAWARE

ELECTRIC SWITCH

Application filed January 28, 1928. Serial No. 250,105.

This invention relates to electric switches and one of its objects is to provide a novel and simple means for securing a wiping action between the switch contacts for the purpose of insuring a good electrical connection between the contacts and also to minimize the accumulation of dirt or metallic oxide upon the engaging surfaces of the contact members.

10 In the present invention this aim is accomplished by providing an electric switch in which a movable contact element is a leaf spring conductor fixed at one end and having a bowed free end, the concave surface of which engages a convex surface provided by a stationary contact. A movable actuating member presses the bowed end of the flexible conductor against a stationary contact and so to speak, tends to iron out the 15 amount of curvature of the bowed end of the spring conductor by an action which causes this bowed end to be laterally displaced relative to the stationary contacts while being maintained in engagement therewith.

20 Further objects and advantages of the present invention will be apparent from the following description, reference being had to the accompanying drawings, wherein a preferred form of embodiment of the present 25 invention is clearly shown.

In the drawings:

Figs. 1 and 2 are side and front end views, respectively, of a switch embodying the present invention.

30 Fig. 3 is a sectional view on the line 3—3 of Fig. 2.

Fig. 4 is a sectional view on the line 4—4 of Fig. 3.

40 Fig. 5 is a sectional view on the line 5—5 of Fig. 3.

Fig. 6 is a sectional view on the line 6—6 of Fig. 4.

45 Figs. 7, 8 and 9 are diagrammatic views showing the relative positions of the switch members in various operating positions.

The switch case is provided by a tubular member 20 interfitting with a metallic end wall provided by a key shaft frame 21, and receiving a nonconducting end wall 22 which 50 may be also the end wall of an ignition coil

housing including a tubular case 23 which encloses primary winding 24, the secondary winding 25 and the center core 26. The primary winding 24 may be connected by wire 27 with a metallic insert 28 embedded in the insulating end member 22 by a molding operation. The insert 28 provides the stationary switch contact and has a somewhat convex end 29 for engagement by the bowed end 30 of a leaf spring conductor 31 which is attached to a rivet 32 having its head embedded in the molded insulating end member 22 as shown in Fig. 6. The insert or rivet 32 is connected by wire 33 with one of the terminals, not shown, of the ignition coil.

The frame 21 supports a key shaft 40 which carries a plurality of laterally moving locking bars 41 which, when the proper key 43 is inserted in the shaft 40, will be moved out of longitudinally extending grooves 42 in the frame 21 and will be so located that their ends are flush with the cylindrical periphery of the shaft 40. Screws 44 attach to the shaft 40, a non-conducting contact actuator 45 and a detent plate 46 having holes or recesses 47 each for receiving a ball 48 which is guided by recess 49 in the frame 21 and which is urged toward the detent plate 46 by spring 50.

Referring to Figs. 7, 8 and 9, in which the operation of the switch is shown diagrammatically, when the switch is off, the operating edge or camming portion 55 of the actuator 45 will be located relative to the bowed end 30 of the contact 31 as shown in Fig. 7 in order to permit the bowed end 30 to be separated from the stationary contact 29 due to the resiliency of the spring blade 31. As the actuator 45 is turned in a clockwise direction as viewed in Fig. 4, the actuator 45 will first engage the bowed end 30 of the conductor 31 along the side of the arch of the bow in order to cause the conductor to touch the contact 29. During further movement of the actuator 45 in a clockwise direction as represented by movement toward the right from the position shown in Fig. 8 to that shown in Fig. 9, during which the actuator 45 rides from the side to the crown of the arch of the bowed end 30, the coaction be-

tween the actuator 45 and the bowed end 30 of the spring 31 is such as to tend to iron out or diminish the curvature of the bowed end 30. During this action the spring conductor 31 will be displaced laterally toward the left with respect to the convex end of the contact 29 in order to produce such a rubbing action as will tend to maintain the contact surface of the switch contacts in a relatively clean 10 condition so as to insure making a good electrical connection.

While the form of embodiment of the present invention as herein disclosed, constitutes a preferred form, it is to be understood that 15 other forms might be adopted, all coming within the scope of the claims which follow.

What is claimed is as follows:

1. An electric switch comprising a leaf spring conductor fixed adjacent one end and 20 having a bowed free end, a stationary contact engageable by the bowed end of said conductor, a housing supporting said contact and conductor, and having interfitting engagement with a metallic end wall, said 25 end wall providing a member engageable with the conductor for causing the bowed end to engage the stationary contact and for modifying the shape of the bowed end while 30 engaging the contact in order to produce a wiping between the conductor and the contact.

2. An electric switch comprising a leaf spring conductor fixed adjacent one end and having a bowed free end, a stationary contact 35 engageable by the bowed end of said conductor, a housing supporting said contact and conductor, and having interfitting engagement with a metallic end wall, a member rotatably supported by said end wall, 40 and means for causing the bowed end to engage the stationary contact and for modifying the shape of the bowed end while engaging the contact in order to produce a wiping between the conductor and the contact.

3. An electric switch comprising a leaf spring conductor fixed adjacent one end and having a bowed free end, a stationary contact engageable by the bowed end of said 50 conductor, a housing supporting said contact and conductor, and having interfitting engagement with a metallic end wall, a lock controlled member provided by said end wall, and means movable in response to said 55 lock controlled member for causing the bowed end to engage the stationary contact and for modifying the shape of the bowed end while engaging the contact in order to produce a wiping between the conductor and 60 the contact.

In testimony whereof I hereto affix my signature.

HARRY E. NORVIEL.
